HOIST CONTROL AND DRIVE

Harry F. Vickers, Detroit, Mich., assignor to Vickers Incorporated, Detroit, Mich., a corporation of Michigan

Application August 3, 1940, Serial No. 350,619

19 Claims. (Cl. 187—28)

1

This invention relates to a hoist control and has particularly to do with a hoist mechanism driven by a hydraulic motor and a hydraulic pump.

It is an object of the present invention to provide a control mechanism which is normally servo-operated but which may be operated without servo power in case of failure of certain elements of the system.

A further object is to provide a servo controlled unit in which the speed signal is limited by the position of the hoist. Another object of the invention has to do with a provision for safely stopping the elevator or hoist in case of power failure.

Another object of the invention has to do with a means for maintaining the hydraulic pressure source at slight output when the motor is inoperative and means for bypassing said output.

Other objects and features of the invention having to do with details of construction and the hydraulic circuit, including the operation of the same, will be brought out in the following description and claims.

In the drawings:

Fig. 1 is a circuit diagram substantially diagrammatic showing the various elements of the system.

Fig. 2 is an enlarged sectional view of a portion of Fig. 1 showing the main elements of the hydraulic control.

In Fig. 1 a hoist car 10 is supported by an operating cable 11 controlled by a drum 12. The drum 12 is driven by a reversible, variable speed, motor 13 through suitable gears 14 and 15. A brake unit 16 is connected to gear 15 by a gear 17. Connected also to the drum 12 through suitable gearing 18 is a cam wheel 19. Housed within a tank 20 are a reversible variable displacement hydraulic pump 21 and a control valve block 22 (see Fig. 2). The pump 21 is driven by a shaft 23 from an electric motor 24 which also drives a pilot or booster pump 25. Tank 20 serves as a main source of liquid for the hydraulic control circuit and a supplemental tank 26 has functions which will be described later.

An electrical circuit is provided to permit operation of the elevator or hoist only when certain conditions are met. A solenoid 30 operates a venting valve 31 in the valve block 22. The venting valve which will be described later is of such a nature that the elevator cannot be operated unless it is shifted against a spring 31a by the energized solenoid 30. The first condition for the movement of the hoist is that the electric

motor 24 be operating. Consequently, the energy of the electric circuit is taken from the motor. One line 32 leads from the motor to the solenoid 30. Another line 33 leads to a switch 34 which is connected to a door 35, shown diagrammatically at the upper station A. From switch 34, which is closed when door 35 is closed, the circuit to solenoid 30 follows a line 36 to a starting switch 37. A line 38 connects through a switch 39 to line 40 leading to solenoid 30. Switch 39 is operatively connected to a door 41 at the lower station B.

At each station, A and B, is provided a limit switch 42 and 43, respectively. When car 10 is 15 at its lower limit, as shown in the drawings, switch 43 is open. When the car reaches its upper position, switch 42 is open. During the travel of the car between the stations the starting switch 37 may be released since both switches 42 and 43 20 will be closed and the circuit between lines 36 and 38 is completed by a line 44, switch 42, a line 45 and switch 43. Line 33 is shunted to line 36 through a line 46 and a switch 47 which is closed when the car 10 is at its upper station by a cam 25 slide 10a on the car. This shunting of line 46 permits operation of the car 10 between two loading levels at the upper station with door 35 open. The switch 42 controls the upper level and a switch 48 in line 45 controls the lower level, the 30 switch 48 having an arm 49 which operates the switch when pressed downwardly but not when pressed upwardly. A small projection 50 on the car is arranged to contact switch 49. Switches 42 and 43 are operated by a projection 51 on the 35 car.

Pump 21 is connected to motor 13 by conduits 55 and 56. The pump 21 has a movable member 57 which, when shifted to the right as viewed in Fig. 2, will cause pressure to be directed from 40 conduit 56 to conduit 55 and thence to the motor to effect a hoisting movement. When the movable member 57 is displaced to the left, there will be a lowering action. Since the weight of the elevator will tend to drive the motor 13, the line 45 55 will be under pressure and fluid will be flowing through pump 21 to line 56. There is a closed circuit between pump 21 and motor 13 and this circuit is super-charged through a check valve 58 open to a line 59 and booster pump 25. In the event of failure of the booster pump, replenishing of line 56 may take place through a conduit 60 and a gravity valve 61 supplied by a tank 26 which is located at a level sufficient to supply a head of oil.

The basic control of the hoist is through the

movable member 57 on pump 21; this member is pivoted as at 52 and normally is shifted by a servo mechanism which controls the movement of a motor piston 63. The piston 63 is located in a cylinder 64 and has a rod 65 connected to a link 66 and by the link to the movable head 57. The rod 65 has a restriction 67 which serves as a valve, as will be described later. The piston 63 is to be shifted by pressure from the booster pump 25, said pressure being conducted to the housing 22 by a line 68. When venting valve 31 is in the position shown in Fig. 2, the solenoid 30 being deenergized, line 68 is vented to a line 69 leading to tank 26. Above the venting valve 31 in housing 22 is a servo-valve 70 and above the servo-valve is a shuttle valve 71. As shown in the drawings, the shuttle valve normally bypasses conduits 72 and 73 leading to the respective ends of cylinder 64. When venting valve 31 is shifted to the left, as viewed in the drawings, by the energization of the solenoid 30, line 68 will be cut off from line 69 and pressure from booster pump 25 will be directed to a line 74. Pressure in line 74 will shift shuttle valve 71 to the right, closing conduit 72 from conduit 73, but opening the end of conduit 74 to conduit 73, thus admitting pressure to the differential end of pressure piston 63. Because of the location of tank 26, and the connection pipe 69, there is a head of oil maintained on lines 72, 73 when the valves are in the position shown and the hoist is not being operated. Consequently, when valve 70 is in the position shown, a shifting of valve 71 to admit pressure to the differential end of piston 63, will not cause shifting of the piston since the liquid to the left of piston 63 cannot escape. The servo-valve 70 is controlled by a rod 75 leading from a shaft 76 controlled by a lever 77.

Assuming that the elevator is to be hoisted, lever 77 is lifted and by this movement rod 75 is raised. Since piston 63 is temporarily stationary, a movement of a bell crank 78 will shift valve 70 to the left, through a lever 78a and link 78b. This will open conduit 72 to tank conduit 69 and permit piston 63 to be shifted to the left by pressure in conduit 73. This will cause a shifting of the movable head 57 to a hoisting position. A restriction 79 in conduit 72 limits the velocity of the piston 63 and, therefore, limits acceleration or deceleration of the hoist. If the hoist is to be lowered, lever 77 is lowered, thus resulting in a downward movement of rod 75. This will shift the valve 70 to the right by reason of the movement of bell crank 78 and lever 78a. Pressure will then be admitted from line 68 to line 72 and the head end of piston 63, thereby shifting it to the right. In each case, of course, a movement of the piston 63 and its rod 65 will compensate for movement of the valve 70 and there will thus be a follow-up or servo movement.

At each side of pump 21 are cylinders 80 and 81 in which are located pistons 82 and 83; these pistons have rods extending to a projection 84 on the movable head 57 and each is urged toward this projection by springs 85 and 86. A conduit 87 connects one end of the cylinder of piston 83 to conduit 56 while the other end is connected by a conduit 88 to conduit 55 and also to housing 22 at the restriction in the rod 65. The cylinder 80 for piston 82 is connected by a conduit 89 to the right end of venting valve 31. When the venting valve is in the position shown, the conduit 89 is connected to a conduit 90 leading to the tank conduit 69. Similarly, with the parts as

shown, the conduit 88 is connected through a conduit 91 to the venting valve and through the venting valve to a conduit 92 leading to conduit 56 of the main pump. Consequently, there is no pressure in either cylinders 80 or 81 and the springs 85 and 86 are free to act. These springs are so adjusted that they will hold the movable head 57 slightly off center toward the hoist side. The output of the pump 21 is, therefore, through conduit 55 but this output is bypassed through conduit 88, the valve restriction 67, conduit 91, venting valve 31 and conduit 92.

The effect of shifting of the venting valve 31 to the right is to connect cylinder 80 to the pressure in conduit 55 through conduit 88, around piston rod 65, through a conduit 93, to conduit 89. Branch 88a also connects cylinder 81 to the pressure in conduit 55. Line 87 is necessary to insure shifting of piston 83 by equal displacement from either line of the closed operative circuit.

In addition to the brake 16, another safety device is provided in a safety latch 95 which is controlled by a spring pressed piston 96. A piston 97 within a cylinder 98 at brake 16 and also the piston 96 are controlled by pressure from the booster pump 25 by reason of lines 99 and 100 leading, respectively, from conduit 68. When venting valve 31 is open, the brake 16 will be engaged and the latch 95 will be engaged providing the car is in its uppermost position. Upon the shifting of valve 31 and the building up of pressure in line 68, piston 96 will be retracted and, similarly, piston 97 will be retracted, thus releasing latch 95 and brake 16.

In case of failure of the booster pump or any of the pressure lines connected therewith, a mechanism is provided to permit operation of the hoist without servo-power. A shaft 101, operable by a lever 102, controls, by suitable arm connections, the piston 96 and the piston 97. For example, if lever 102 is shifted from its P position to its W position, latch 95 will be retracted and brake 16 will be released. A further connection is provided, through a rod 103, so that upon such shifting of lever 102, the valve 70 will be locked in its neutral position as viewed in Fig. 2. The locking of valve 70 is accomplished by a cam 104 which is moved by the shifting of rod 103. Since, due to booster pump failure, pressure is absent from lines 68 and 74, the valve 71 is spring impelled to bypass the stroke cylinder lines 72 and 73 to the replenishing tank line 69. Stroke piston 63 is, therefore, allowed free movement and the differential bypass is compensated for by the connection with tank 26. The head of oil from the tank 26 prevents aeration. Manual application at lever 77 now controls the pump head 57 without lost motion through rod 75, bell crank 78 and lever 78a, which is now pivoted at link 78b. Replenishing of the operating circuit is obtained through gravity check 61 from tank 26. The remainder of the circuit functions the same as previously described.

The tank 26 is fed by surplus oil from the booster pump through line 105 and check valve 106. The overflow from this tank is carried through line 107 to tank 20. The booster pump normally draws oil through oil filters 108 in tank 20 and a conduit 109. These two filters are mounted parallel in the circuit and are provided with plunger operated check valves. By this means one of them may be removed at a time while the other is operating. Air line 110 transfers air between tanks 20 and 26 due to fluid dis-

placement. When the booster pump 25 is vented through valve 31, a restriction 111 maintains a back pressure in line 59 thus keeping the operating circuit supercharged even while idling.

Cam 19 limits the amount the lever 77 may be shifted. As the lever shaft 76 is also connected, as previously described, to a servo-valve 70 which controls pump offset, it can be seen that cam 19 controls the maximum rate of speed as well as deceleration and acceleration of the hoist. This is accomplished by reason of a lever or follower 112 which rides on the circumference of the cam which is properly shaped to control the movement of the shaft in conjunction with the movement of the motor 13 and the hoist car 10. A cam 113 on car 10 is arranged to contact a lever 114 on its movement from the top level at the upper station to the lower level to cause deceleration as the hoist is moved between levels at the upper station. This is accomplished through a rod 115 which connects to the shaft 76.

An object of the present invention has been to provide a hoist circuit which will perform safely even in the event of power failure or rupture of any of the lines. In case of power failure, that is, failure of the electric power driving motor 28, means has been provided to stop the hoist in the smoothest and safest possible manner. While in the lowering stroke, it will be noted that line 88 remains open to line 91 through the restriction 67 in rod 65 of stroke piston 63. In the event of power failure while lowering, the solenoid 38 would be deenergized and the spring 31a will shift the valve 31 to a venting position. The result will be a centering of the pump yoke 57 by the spring pressed plunger or piston 82 and at the same time, the operating circuit is bypassed through lines 88, 91, 92, a check valve 117, and a restriction 118. A sufficient resistance is thus affected in this bypassing to aid the brake 16 in gradually bringing the load to a safe stop. The brake, of course, will be automatically engaged upon a shifting of valve 31 to venting position. In the case of power failure while hoisting, line 88 is closed by rod 65 since piston 63 is shifted to the left and hence the pump 21 will continue to raise the hoist carried on by the inertia by the high speed electric motor. Brake 16 will, of course, be engaged as before but a free wheeling device shown diagrammatically at 119, permits overrun while hoisting. The load is thus gradually decelerated by reason of gravity and this prevents the cable from whipping. As soon as the load comes to stop, the brake 16 will function to hold it and also the pressure will drop in line 55 thus permitting the plunger 83 to center the pump yoke. It will be seen that the pump yoke is always centered as a result of power failure and, as a consequence, the electric motor is lightly loaded upon resumption of power.

It will further be seen that in the event of the rupture of any of the pressure lines, the brake 16 will be engaged. In the event of the rupture of line 56, the booster pump pressure would be vented through line 59 and check valve 58 thus causing an engagement of brake 16. Rupture of line 55 would also vent the booster pump pressure through check valve 120, again causing the engagement of brake 16.

I claim:

1. In a hoisting mechanism and control, an elevating mechanism, a hydraulic motor for driving said mechanism, and a pumping circuit for furnishing liquid under pressure to drive said motor including a variable displacement pump,

means on said pump shiftable to "hoist" or "lower" positions for controlling the direction and volume of flow, and means acting on said shiftable means to maintain it slightly toward a hoist position when the motor is not being operated.

2. In a hoisting mechanism and control, an elevating mechanism, a hydraulic motor for driving said mechanism, and a pumping circuit for furnishing liquid under pressure to drive said motor including a variable displacement pump, means on said pump shiftable to "hoist" or "lower" positions for controlling the direction and volume of flow, control means acting on said shiftable means to maintain it slightly toward a hoist position when the motor is not being operated, and valve means for bypassing the slight "hoist" output of said pump when said motor is not being operated.

3. In a hoisting mechanism and control, an elevating mechanism, a hydraulic motor for driving said mechanism, and a pumping circuit for furnishing liquid under pressure to drive said motor including a variable displacement pump, means on said pump shiftable to "hoist" or "lower" positions for controlling the direction and volume of flow, control means acting on said shiftable means to maintain it slightly toward a hoist position when the motor is not being operated, valve means for bypassing the slight "hoist" output of said pump when said motor is not being operated, and additional means responsive to a predetermined operating signal for removing the effect of said control means and cutting off said bypass.

4. In a hoisting mechanism and control, an elevating mechanism, a hydraulic reversible motor for driving said mechanism, and a pumping circuit for furnishing liquid under pressure to drive said motor including a variable displacement pump, means on said pump shiftable to "hoist" or "lower" positions for controlling the direction and volume of flow, control means acting on said shiftable means to maintain it slightly toward a "hoist" position when the motor is not being operated comprising spring pressed plungers located in cylinders, valve means for bypassing the slight "hoist" output of said pump when said motor is not being operated, and additional means responsive to a predetermined operating signal for cutting off said bypass and directing said pump output to said spring pressed plungers to remove the effect thereof on said shiftable means.

5. In a hoisting mechanism and control, an elevating mechanism, a hydraulic reversible motor for driving said mechanism, and a pumping circuit for furnishing liquid under pressure to drive said motor including a variable displacement pump, shiftable means on said pump movable to "hoist" or "lower" positions for controlling the direction and volume of flow, spring pressed plungers acting on said shiftable means to maintain the same slightly toward a hoist position when the motor is not being operated, an independent source of pilot pressure, a pressure operated means responsive to said pilot pressure and to a predetermined operating signal to control the position of said shiftable means during operation of said motor, and a valve means arranged to bypass the slight "hoist" output of said pump and to bypass the pilot pressure when the motor is not being operated, and shiftable to direct said pilot pressure to said pressure operated means and to direct said pump output to

said plungers to remove the effect thereof on said shiftable means.

6. In a hoisting mechanism and control, an elevating mechanism, a hydraulic motor for driving said mechanism, a control cam driven by said motor, a pumping circuit for furnishing liquid under pressure to drive said motor including a variable displacement pump, means on said pump shiftable to "hoist" or "lower" positions for controlling the direction and volume of flow by its relative displacement from a neutral position, an operating lever, means operably connecting said lever and shiftable means whereby shifting of said lever will effect displacement of said shiftable means, and means connecting said lever and said cam whereby the limits of movement of said lever and said shiftable means are directly controlled by the position of said cam in its movement with the motor, said cam being shaped to control acceleration and deceleration of said motor.

7. In a hoisting mechanism and control, an elevating mechanism, a hydraulic motor for driving said mechanism, a variable delivery reversible pump for furnishing liquid under pressure to said motor, a movable member on said pump to control the output thereof, a source of pilot pressure, a follow-up valve for utilizing said pilot pressure to shift said movable member, a brake means for said motor and a safety latch for said elevating mechanism, means connected with said brake means and said safety latch whereby said pilot pressure functions at the instance of an operator to release the same, and an independent mechanism operable upon failure of said pilot pressure to unlock said safety latch, release said brake, and render said follow-up valve inoperable.

8. In a hoisting mechanism and control, a hydraulic motor for driving a hoist mechanism, a reversible variable delivery pump for furnishing liquid under pressure to drive said motor, a movable member on said pump for controlling, by its displacement, the direction and volume of flow from said pump to said motor, a source of power for driving said pump, and means responsive to a failure of said source of power for bypassing said pump during a lowering movement of said hoist.

9. In a hoisting mechanism and control, a hydraulic motor for driving a hoist mechanism, a reversible variable delivery pump for furnishing liquid under pressure to drive said motor, a movable member on said pump for controlling, by its displacement, the direction and volume of flow from said pump to said motor, a source of power for driving said pump, means responsive to a failure of said source of power for bypassing said pump during a lowering movement of said hoist, and means for restricting said bypass flow to cause gradual deceleration of said hoist.

10. In a hoist, a driving mechanism comprising a motor, a variable displacement pump for furnishing liquid under pressure to said motor, movable means on said pump for controlling the direction and volume of flow, a follow-up mechanism for actuating said movable member, comprising a hydraulic motor, a valve for controlling pilot pressure thereto and means connecting the same to effect follow-up movement, manual means for controlling said valve, and means for locking certain elements of said follow-up mechanism to permit direct manual operation in case of failure of pilot pressure.

11. In a hoist, a driving mechanism comprising

a motor, a variable displacement pump for furnishing liquid under pressure to said motor, movable means on said pump for controlling the direction and volume of flow, a follow-up mechanism for actuating said movable member comprising a hydraulic motor, a valve for controlling pilot pressure thereto and means connecting the same to effect follow-up movement, manual means for controlling said valve, brake means for locking said motor except when released by pilot pressure, and means for locking certain elements of said follow-up mechanism and for releasing said brake means to permit direct manual operation in case of failure of pilot pressure.

12. In a hoist driving system, a hydraulic motor, a pump for furnishing pressure thereto, a closed circuit connecting said pump and said motor, a pilot pump for furnishing replacement liquid to said closed circuit, a liquid supply tank mounted at a level above said circuit, and a valve connecting said tank with said circuit whereby said tank may furnish replacement liquid to said closed circuit in event of failure of said pilot pump.

13. In a hoisting system, a hoisting element, power means for actuating the same between a lower station and an upper station, gate means at each of said stations to prevent access to the path of movement of said element while it is between said stations, a control system operatively connecting said gate means with said power means whereby said element may be shifted between said upper and lower stations only when said gate means are properly closed, and means for permitting limited movement of said element between two defined and spaced levels at the upper station when said upper gate is open.

14. In a hoisting system, a hoisting element, power means for actuating the same between a lower station and an upper station, gate means at each of said stations to prevent access to the path of movement of said element while it is between said stations, a control system operatively connecting said gate means with said power means whereby said element may be shifted only when said gate means are properly closed, means for permitting limited movement of said element between two levels at the top station when said top gate is open, and means for automatically decelerating said element at the lower end of its movement between levels at the upper station.

15. In a hoisting mechanism and control, a hydraulic driving motor, an elevating mechanism to be driven by said motor, a pumping circuit including a variable delivery pump for furnishing liquid under pressure to drive said motor, lines connecting the respective inlets and outlets of said motor and pump, a pressure release-brake operably connected to said mechanism for braking against downward movement only of said hoist, control means for bypassing said pump-motor lines, control means for controlling pressure to said brake, electric power means for controlling said control means, and means responsive to power failure during hoisting to operate said control means to effect engagement of said brake to hold said hoist as it comes to rest, and responsive to power failure during lowering to open said bypass and effect engagement of said brake to bring said mechanism to rest.

16. In a hoisting mechanism and control, a hydraulic driving motor, an elevating mechanism to be driven by said motor, a pumping circuit including a variable delivery pump for furnish-

ing liquid under pressure to drive said motor, lines connecting the respective inlets and outlets of said motor and pump, a pressure release-brake operably connected to said mechanism for braking against downward movement only of said hoist, control means for bypassing said pump-motor lines, control means for controlling pressure to said brake, electric power means for controlling said control means, means responsive to power failure during hoisting to operate said control means to effect engagement of said brake to hold said hoist as it comes to rest, and responsive to power failure during lowering to open said bypass and effect engagement of said brake to bring said mechanism to rest, and means forming a restriction in said bypass to aid in slowing down said motor during power failure in lowering.

17. In a hoisting mechanism and control, an elevating mechanism, a hydraulic motor for driving said mechanism, and a pumping circuit for furnishing liquid under pressure to drive said motor including a variable displacement pump, means on said pump shiftable to "hoist" or "lower" positions for controlling the direction and volume of flow, means acting on said shiftable means to move the same to substantially neutral position in the absence of operating pressure in said pumping circuit but rendered inoperable by operating pressure, a pressure release-brake operably connected to said mechanism for braking against downward movement only of said hoist, control means for bypassing said pumping circuit, control means for controlling pressure to said brake, electric power means for controlling said control means, and means responsive to power failure during hoisting to operate said control means to effect engagement of said brake to hold said hoist as it comes to rest, and responsive to power failure during lowering to open said bypass and effect engagement of

said brake to bring said mechanism to rest, said shiftable means being returned to substantially neutral position by the means acting thereon in each case of power failure.

5 18. In a hydraulic mechanism and control, an operating mechanism, a hydraulic motor element for driving said mechanism, a pumping circuit for furnishing liquid under pressure to drive said motor element including a pump element, means on one of said elements shiftable to positions for controlling the direction and volume of flow by its relative displacement from a neutral position, an operating lever, means operably connecting said lever and shiftable means whereby shifting of said lever will effect displacement of said shiftable means, and means operably connecting said lever and said operating mechanism to limit the movement of said lever and said shiftable means in a varying degree dependent on the position 10 of the operating mechanism in its movement with the motor.

19. In a hydraulic mechanism and control, an operating mechanism, a hydraulic motor element for driving said mechanism, a pumping circuit for furnishing liquid under pressure to drive said motor element including a pump element, means on one of said elements shiftable to positions for controlling the direction and volume of flow by its relative displacement from a neutral position, 25 an operating lever, means operably connecting said lever and shiftable means whereby shifting of said lever will effect displacement of said shiftable means, a cam operated by said motor, and means connecting said lever and said cam comprising a cam follower mounted on said lever adapted to follow said cam and to limit the movement of said lever in varying degrees dependent on the movement of the motor from its 30 starting position.

HARRY F. VICKERS.
